UNITED STATES PATENT OFFICE.

LORIN W. YOUNG, OF NEW YORK, N. Y.

DESIGN FOR A LIGHTING-FIXTURE.

46,936.

Specification for Design.

Patented Feb. 9, 1915.

Application filed October 27, 1914. Serial No. 868,915. Term of patent 7 years.

To all whom it may concern:

Be it known that I, LORIN W. YOUNG, a citizen of the United States, residing at New York city, in the county of New York and State of New York, have invented a new, original, and ornamental Design for a Lighting-Fixture, of which the following is a specification, reference being had to the accompanying drawing, forming part thereof.

In the drawings Figure 1 is a side view

of the fixture and Fig. 2 is an end view thereof.

I claim:—

The ornamental design for a lighting fixture as shown.

LORIN W. YOUNG.

Witnesses:

M. D. KUHN,

M. A. KIRK.
